ELMER E. NEAL, OF NEW HAVEN, CONNECTICUT, ASSIGNOR TO PEERLESS HANDCUFF COMPANY, OF SPRINGFIELD, MASSACHUSETTS, A CORPORATION OF MASSACHUSETTS

LOCK MECHANISM

Application filed October 24, 1929. Serial No. 402,190.

This invention relates to an improvement in lock mechanism particularly designed to restrain the movements of a prisoner's limbs as used in handcuffs, thumb-cuffs, leg irons, and any such devices used by officers.

According to one feature of the invention, a novel mechanism is provided which is very rugged and can withstand an exceptional amount of abuse without getting out of order. The design is such that the parts can be made and assembled without requiring any nice or skillful fitting operations. Other features of novelty and utility will be apparent from the detailed description and annexed claims.

The invention is shown, for purposes of illustration, in the form of a handcuff where its features find particular utility.

In the drawings—

Fig. 1 is a plan view of one of a pair of handcuffs embodying the invention. In this view the lock casing has one of its side plates removed to expose the parts of the lock mechanism in their assembled relation;

Fig. 2 is a view of the filler piece having recesses for various movable parts of the mechanism;

Fig. 3 is a detail view of the spring latch;

Fig. 4 is a detail view of the lock cylinder;

Fig. 5 is a detail view of the cylinder catch;

Fig. 6 is a cross section of Fig. 4 on line 6—6; and

Fig. 7 is a view of one form of key that may operate the lock.

The handcuff is preferably made up of a double arm half comprising spaced frame members 1 and 2. The locking arm 3 is pivoted at 4 between arms 1 and 2. Between the latter at the end opposite pivot 4 a filler piece 5 is riveted. This piece 5 with portions of arms 1 and 2 serving as side plates form the lock casing. Arm 3 has a peripheral toothed arc portion 6 struck from pivot 4 as a center. With this construction it is clear that arm 3 may move (counterclockwise) for arm 6 to sweep by the top wall of the lock casing and it may continue all the way around and repeat so long as no wrist is em-

braced. It is for this form of handcuff that my invention is particularly useful.

The filler pieces 5 has a recess to receive the spring latch 7 mounted against coiled spring 8 at the bottom of the recess. The spring tends to keep the latch in position to engage the teeth of arc 6 as the latter passes the lock casing and to thus permit one line of movement for arm 3 by ratcheting against the spring and to prevent the opposite line of movement. The latch has a lug 9 extending into a circular recess 10 of the lock casing whereby the key operated part may draw the latch back and release arm 3 to unlock a wrist.

The recess 10 is preferably circular and the cylinder 11 is mounted by tenons 12, one engaged in a suitable recessed bearing in each of the side plates of the lock casing to rotate in said recess. The cylinder 11 has a tooth 13 adapted to engage lug 9, and also a little recess 14 in its periphery to be engaged by a spring-pressed detent 15.

The key 16 is inserted through a key hole in one of the side plates and preferably has a shank extension as seen at the bottom of Fig. 7 to protrude through a hole in the opposite side plate to get a good bearing for turning. The key is adapted to strike a lug 17 on the inside of the cylinder by which it gets a purchase to turn cylinder 11 in its bearings. The turning has to overcome the friction of detent 15 and when tooth 13 engages lug 9, also the resistance of the latch spring. When turned for enough, detent 15 engages recess 14 with enough pressure to hold latch 7 depressed without pressure from the key. Thus the key can be used to pull the latch down to a point where it will stay and the officer's hands are then free to pull arm 3 back to free the prisoner's wrist.

Another pin or lug 18 at the opposite side of the key requires the cylinder to be rotated back to its original position where the parts are ready for spring latching before the key can be lined up with the key hole and removed. Thus, the officer necessarily resets the mechanism after each unlocking operation because he must do that before he can remove the key. And he always removes the

key when he puts the handcuffs back in his pocket ready for the next use.

In assembling my lock I place the cylinder 11 in one side plate, put the parts 7, 8, and 11 in the proper recesses of the filler piece, put on the second side plate, and rivet the two side plates together with filler piece between. To hold cylinder 11 in proper relative position I may provide another peripheral notch like 14 for engagement with detent 15 when the parts are in latching position for the key to be inserted.

From the description and drawings it can be seen that I have provided a rugged lock casing and locking means that can stand a great deal of abuse without danger of getting out of order. The lock casing is almost a solid rigid piece, since it has only recesses for the necessary and small movements of each related part. At no part of the lock casing is there any substantial hollow portion that leaves the walls relatively weak or susceptible to being crushed in by a blow from the outside. On the contrary there is such a rugged arrangement of completely supported parts that the whole mechanism would withstand hammer blows about as well as if the bulk of the lock casing were of solid material. Furthermore, the locking parts are so arranged that there is an extremely small possibility of any of them being pounded out of properly functioning position and condition. These advantages and others are attained by an extremely simple coordination of parts which is novel with respect to the easy manufacture and desired utility of this type of lock mechanism.

What I claim is:

1. A prisoner's locking device comprising a clasping means formed of pivoted arms having a lock casing and mechanism to permit complete rotation in one direction only, said mechanism including within the lock casing a spring latch movab'e only in a straight line, a rotatable key operable part to release the latch, and teeth on one of the pivoted arms arranged to ratchet by said latch in one direction and be stopped thereby in the other direction, and a spring detent to releasably hold said rotatable part in latch releasing position.

2. A prisoner's clasping means including a lock casing, a rotatable key engageable member in the casing, a spring pressed latch, cooperating lugs on said member and latch by which a rotation of the former will move the latch out of operable position, a spring pressed detent to hold the said parts in said last named position.

3. A prisoner's shackle comprising two parallel spaced arms, a locking arm pivoted between the ends of the spaced arms, a filler piece fastened between the arms at the opposite ends and forming with them a lock casing, a rotatable member mounted in a recess

of the filler piece for engagement and rotation by a key, a spring pressed latch reciprocable in a straight line about tangent to said rotatable member and having a part engageable thereby for retraction against the spring pressure, teeth on said locking arm engageable by said latch to permit movement of said arm past the lock casing only in one direction until the latch is moved back against its spring.

4. A prisoner's shackle comprising two parallel spaced arms, a locking arm pivoted between the ends of the spaced arms, a filler piece fastened between the arms at the opposite ends and forming with them a lock casing, a rotatable member mounted in a recess of the filler piece for engagement and rotation by a key, a spring pressed latch reciprocable in a straight line about tangent to said rotatable member and having a part engageable thereby for key action against the spring latch pressure, teeth on said locking arm engageable by said latch to permit movement past the lock casing only in one direction until the latch is moved back against its spring, and a spring detent adapted to hold the rotatable member when the key has operated it to hold the latch against its spring.

In testimony whereof I have affixed my signature.

ELMER E. NEAL.
